[57] CLAIM

The ornamental design for a shoe sole, as shown and described.

DESCRIPTION

FIG. 1 is a bottom plan view of a shoe sole showing my new design;

FIG. 2 is a left side elevational view thereof;

FIG. 3 is a right side elevational view thereof;

FIG. 4 is a front elevational view thereof;

FIG. 6 is a bottom plan view of a shoe sole showing an alternate embodiment of my new design;

FIG. 7 is a left side elevational view thereof;

FIG. 8 is a right side elevational view thereof;

FIG. 9 is a front elevational view thereof; and

FIG. 10 is a rear elevational view thereof.

The broken line showing of a shoe upper in FIGS. 1-10 and the area within are environmental only and form no part of the claimed design.

FIG.1**FIG. 2****FIG. 3****FIG.4****FIG.5****FIG.6****FIG.7****FIG. 8****FIG. 9****FIG. 10**
